UNITED STATES PATENT OFFICE

HENRY J. BROWNSTEIN, OF CHICAGO, ILLINOIS

DEODORANT HOLDER

Application filed May 15, 1931. Serial No. 537,586.

The object of this invention is to provide a novel deodorant holder for use in urinals.

The improved holder, which is adapted to be positioned at the location of the drain, serves not only as a container for the deodorant but as a strainer for refuse as well. The holder is neat in appearance, is easy to refill, will not interfere at all with drainage, and will not clog up. The holder is further 10 more durable in construction and inexpensive to manufacture. By reason of its location at the drain, the holder will be kept clean by the flushing devices ordinarily employed, and the objectionable odors will all 15 be eliminated at their source.

While the foregoing statements are indicative in a general way of the nature of the invention, other objects and advantages will be apparent upon a full understanding of the 20 construction, arrangement and function of the parts which make up the holder.

One form of the invention is presented herein by way of exemplification, but it will of course be appreciated that the invention 25 is capable of being incorporated in other structurally modified forms coming equally within the scope of the appended claims.

In the accompanying drawing:

Fig. 1 is a perspective view of a urinal 30 equipped with the combined strainer and deodorant holder of the invention;

Fig. 2 is a vertical section through the center of the holder;

Fig. 3 is a side view of the various parts of 35 the holder, showing the same in separated relation; and

Fig. 4 is a plan view of the holder.

As will be observed in the drawing, the holder includes a dome-like, generally semi-spherical strainer cap 10 which is preferably 40 provided with a flat radially flanged rim 11. The cap 10 is carried by an openwork spider 12 which is enclosed by the cap and is adapted to be attached to the usual drain plate 45 13 in the bottom of the urinal.

The spider 12 is characterized by an upright center post 14 and by a plurality of radially extending arms 15 near the lower end of the post. The arms 15, which are 50 preferably provided with upturned tips 16,

serve to support a specially shaped annular block 17 of deodorizing or disinfecting material. The upper portion of the post 14 serves to center the block on the spider, while the lower portion of the post below the arms serves to space the arms and consequently the block, from the drain plate 13.

The spider 12 is attached to the drain plate 13 by means of a threaded stud 18, which stud projects downwardly from the lower end of the post 14, extends through one of the perforations 19 in the drain plate and is held rigidly against withdrawal by means of a nut 20. When attaching the spider 12, the drain plate 13 is disconnected from the urinal by taking out the usual fastening screws 21. After the spider has been attached, the drain plate is replaced.

The cap 10 is detachably secured to the spider 12 by means of a screw 22 which extends downwardly through an aperture 23 in the center of the top of the cap into a threaded bore 24 at the top of the post 14. The head of the screw 22 may be of ordinary construction, or it may be provided with some special tool-engaging formation, such as a pair of small holes 25, for coaction only with a specially designed tool whereby to prevent unauthorized removal. The cap 10 is drawn down tightly by the screw 22 into a position wherein the rim 11 of the cap is in snug contiguous engagement with the margin of the drain plate 13; as clearly shown in Fig. 2. The over-all diameter of the cap is preferably about the same as the diameter of the drain plate, but obviously may be either smaller or larger without sacrificing any of the more important advantages of the invention.

The cap 10 is provided in the lower portion of the side wall thereof with a large number of narrow vertically extending drainage slots 26, which slots will allow unrestricted flow without permitting the passage of any refuse matter such as cigarette butts, matches, etc. Above the narrow slots 26, near the top, the cap is provided with a relatively small number of wider slots 27, in the nature of flood outlets. These slots, 102

while larger than the slots 26, are still sufficiently small to prevent the entry of all but possibly fine bits of refuse. Because of the openwork formation of the spider 12, and the 5 clearance between the side walls of the cap and the block and arms, any refuse which finds its way into the cap will be flushed down through the same past the block and the spider and will leave through the openings 10 19 in the drain plate.

The device which forms the subject matter of the invention is very easy to install. It is merely necessary to unscrew the drain plate 13 from the urinal, bolt down the 15 spider 12 to the top of the drain plate, and then screw the drain plate back over the drain. After this has been done, the block 17 of deodorizing or other material is fitted down over the spider, as shown in Fig. 20 3, the cap 10 is placed over the spider and block, and the screw 22 is inserted, clamping the assembly together in the manner shown in Fig. 2.

After the block 17 has been completely 25 volatilized, it may be replaced with a new block by merely backing off the screw 22 and lifting the cap 10. It is not necessary even to touch the device when refilling the same, since the point of a screw driver or other 30 tool may be inserted through one of the slots 28 in the upper portion of the cap to lift the same after the screw 22 has been backed off far enough to be disengaged from the post 14.

35 By making the block 17 in the form of an annulus, it will sleeve over the center post 14 of the spider and will give a relatively large volatilizing surface which will remain substantially constant, since the inner 40 surface will increase in area while the outer surface is decreasing in area. The block 17 is referred to herein as being made of a deodorizing material, but it may of course be made instead of a disinfecting material or of 45 a combination of differently functioning materials, and the word "deodorizing", appearing in certain of the following claims is intended to include within its meaning other differently functioning materials.

50 I claim:

1. In a device of the character described, an openwork spider having an upright stem at its center and a plurality of fingers which radiate from a point just above the bottom of the stem into widely separated relation to each other, which spider is adapted to receive a centrally apertured block of deodorizing material with the bottom of the block resting on the fingers, means for fastening the 60

bottom of the stem to the drain plate of a urinal with the fingers in spaced relation to the drain plate, a removable strainer cap cupped over the spider with the rim of the cap in substantial abutment with the drain plate, which cap is provided with a large number of narrow vertically extending slots below the level of the fingers and is provided with a smaller number of much larger downwardly opening slots above the level of the fingers, and means at the center of the top of the cap for detachably securing the latter to the top of the stem of the spider. 75

2. In a device of the character described, an openwork spider having an upright stem at 80 its center and a plurality of fingers which radiate from a point just above the bottom of the stem into widely separated relation to each other, which spider is adapted to receive a centrally apertured block of deodorizing material with the bottom of the block resting on the fingers, means for fastening the bottom of the stem to the drain plate of a urinal with the fingers in spaced relation to the drain plate, a removable strainer cap cupped over the spider with the rim of the cap in substantial abutment with the drain plate and with the sides of the cap in spaced relation to the extremities of the fingers, which cap is provided with a large number of narrow vertically extending slots below the level of the fingers and is provided with a smaller number of much larger downwardly opening slots above the level of the fingers, and a screw 85 passing down through an aperture in the center of the top of the cap into a threaded bore in the center of the top of the stem for detachably securing the cap to the spider. 90

3. In a device of the character described, a cup-shaped housing provided with a flat outturned rim for attachment over a drain opening, and an openwork support within the housing above the rim for holding deodorant material, said housing being provided in the top thereof above the deodorant support with a number of large downwardly directed openings and being provided in the side walls thereof below said support with a relatively large number of narrow vertically elongated slots, which slots start substantially at the base of the rim and extend upwardly in the side walls as far as the support, whereby to form in effect a closely arranged vertical strip enclosure for the chamber present in the housing below the deodorant support. 110 115 120

In testimony whereof I have hereunto subscribed my name.

HENRY J. BROWNSTEIN.
